UNITED STATES PATENT OFFICE.

CLIFFORD D. UPTON, OF PIQUA, OHIO, ASSIGNOR TO THE PIQUA HANDLE & MANUFACTURING COMPANY, OF PIQUA, OHIO, A CORPORATION OF OHIO.

DESIGN FOR A COLOR-MIXER.

57,955.

Specification for Design.

Patented May 17, 1921.

Application filed December 14, 1920. Serial No. 430,763. Term of patent 14 years.

To all whom it may concern:

Be it known that I, CLIFFORD D. UPTON, a citizen of the United States, residing at Piqua, in the county of Miami and State of Ohio, have invented a new, original, and ornamental Design for a Color-Mixer, of which the following is a specification, reference being had to the accompanying drawings, forming a part thereof.

Fig. 2 is a side elevation.

Fig. 3 is a bottom end elevation of the color mixer showing my new design.

I claim:

The ornamental design for a color mixer, as shown.

CLIFFORD D. UPTON.
